UNITED STATES PATENT OFFICE.

EBEN GEORGE DOLAND, OF STARKSBORO, VERMONT.

AIRSHIP PROPELLER.

Application filed August 23, 1922. Serial No. 583,756.

To all whom it may concern:

Be it known that I, EBEN GEORGE DOLAND, a citizen of the United States, and a resident of Starksboro, in the county of Addison and State of Vermont, have invented a new and Improved Airship Propeller, of which the following is a full, clear, and exact description.

This invention relates to propellers for airships, and more particularly aims to provide a new and improved propeller of the type including a revoluble frame or support carrying eccentrically thereon a fractionally rotatable propeller blade or several such blades.

In propellers of the above general character, the axes of revolution of the support and blades are horizontal, and, thus, as the support revolves the ability of the blade itself to rotate on the support permits the employment of various mechanisms in association with the fixed support, the revoluble support, and a blade, as heretofore suggested, whereby the blade is automatically variously tilted at different points in the course of a complete revolution of the revoluble support; thus permitting the blade to act almost like a bird's wing. That is to say, the blade being adjustable to have a large angle of incidence on the downward sweep thereof and a very small angle of incidence on its upward sweep, may act in a lifting as well as a propelling capacity and will generally show increased efficiency when considered solely as a propeller.

An important object of the present invention is to provide such a propeller, one simply constructed and positively controlled and having associated therewith new and improved controlling mechanism of sturdy and reliable construction and very compactly carried, and particularly so carried as to reduce head resistance to a minimum.

A further object of the invention is to provide an arrangement such as that described and one also including means for automatically forcibly urging a blade at the required instant to assume a particular degree of tilt which would otherwise have to be made unaided against the resistance of the atmosphere to an increased angle of incidence of the blade. By the provision of such a means stresses and strains on the controlling mechanism, on the revoluble frame and on the blade itself are largely overcome.

The objects above named will be better understood and how far the present invention goes to satisfy them, will be more clearly appreciated upon reference to the following description to be taken in connection with the accompanying drawings showing an illustrative embodiment of the invention as now preferred.

With these objects and others in view, however, the invention consists in the arrangement of elements and combinations of parts as defined in the appended claims; and, of course, the invention is not to be restricted to the precise details of construction disclosed or suggested herein in connection with the description of the exemplifying subject matter of the drawings.

In these drawings in which like reference characters designate the same parts in the several views—

Figure 1 is a longitudinal or fore-and-aft section taken on line 1—1 of Figure 3;

Fig. 2 is a view similar to Fig. 1, but taken on line 2—2 of Fig. 3;

Fig. 3 is a horizontal section taken on line 3—3 of Fig. 1; and

Fig. 4 is a transverse vertical section taken on line 4—4 of Fig. 1.

Now referring to the drawings, a support or frame 6 is revoluble about a median horizontal axis by virtue of being secured on a shaft 7 journaled at opposite ends in suitable stay members 8 and 8^a running fore-and-aft of the aeroplane body. In the present case the fore-and-aft center line of the aeroplane may be assumed to be located somewhere above and parallel with stay member 8^a of Fig. 1; and the elements shown may be assumed to represent one of a pair of propellers arranged like a pair of bird wings on opposite sides of a central aeroplane body or fuselage. Of course, two or more of such frames, together with the associated parts to be below described, may be employed; but the description here given will be confined to a single group of such elements as tending to simplify the disclosure. It will be understood further that if a pair of such groups is employed, they will be arranged on the aeroplane in balanced relation, but preferably with the axes of rotation of each frame and blade of each group parallel. For convenience of explanation, the airship is here assumed to be travelling forward from the right to the left of Figs. 1 and 3 and the frame 9 is as-

sumed to be revolving in the direction indicated by the arrow in Fig. 1.

The frame or support 6 is rectangular and elongated in a fore-and-aft direction when 5 taking the horizontal during each of its revolutions.

This revoluble support or frame 6 carries a pair of vanes, blades or wings 9. The number of blades here employed is two, but, 10 of course, one or any number may be used. In case more than two blades are provided to be driven about shaft 7, and such blades are as large as the blades illustrated, as is preferred, one or more frames similar to the 15 frame 6 may be carried by shaft 7 with the blades suitably angularly spaced and intersecting at shaft 7. The two blades illustrated are advantageously employed as shown, however, each blade 9 being elongated 20 transversely to the frame and each blade having a width almost as great as one-half the length of the frame. Such an efficient structure is rendered practicable by the provision, according to the present invention, of 25 the particularly simple and rugged means disclosed and hereinafter in detail described, for controlling the various tiltings of the blades, and is further made practical by the provision of automatically functioning 30 means, also described in detail hereinafter, adapted automatically to properly assist in the tilting of a blade 9 to change its tilt in such a way as ordinarily would meet with increased air resistance due to enlarging the 35 angle of incidence of such blade.

Each blade 9 is secured to a shaft 10 journaled at its opposite ends in side-frames 6^a and 6^b of the frame 6. The shaft 10 for each blade is preferably at the middle of 40 the blade.

In order to revolve the frame to sweep the blades through circular paths, a chain 11 may be provided driven from a suitable source of power (not shown) and running 45 over a sprocket 12 fixed on shaft 7.

The controlling mechanism for the blades 9 to cause them to feather or change their angle of incidence, as they commence their forward and backward sweeps relative to 50 the direction of flight of the aeroplane, includes the following parts: A continuous cam-rib 13 providing continuous inner and outer cam surfaces is formed on a disk-like member or plate 14, fixed, as shown, on stay 55 member 8^a of the aeroplane body. This plate 14 is thus vertically arranged to lie in a fore-and-aft plane and to present minimum head resistance in the line of flight of the aeroplane. The shaft 7, of course, 60 passes loosely through the plate 14. Two pairs of rollers 15 engage the cam-rib at diametrically opposite points, one roller of each pair riding against the inner surface of the cam-rib and the other roller of each 65 pair riding against the outer surface of

such rib. Each roller of the two pairs is suitably mounted, as indicated best in Figs. 2 and 3, for spinning on a slide 16. Two of such slides are provided, each carrying a rack 17. The slides are independently movable and each works in a pair of guides 18 on the side member 6^b of frame 6. The rack 17 of each slide meshes with a spur gear 19 secured on the shaft 10 of the adjacent blade 9. Thus the guides, racks, slides and 70 gears, as well as the cam-rib and its supporting plate and the rollers or cam followers 15 are all disposed between the side members 6^b of frame 6 and the stay member 8^a of the aeroplane body. 75

The cam-rib 13 while continuous, is composed of sub-divisions of different curvatures, but preferably with no abrupt changes of curvature; so that, unlike certain suggestions already made, the composite curvature of such cam-rib in general is preferably of a circular character at first glance, as clearly shown in the drawings, thus preventing sudden and frequent shocks to any part of the propeller structure. The curvature just described for the cam-rib is that now deemed preferable, but, of course, may be varied largely so long as the ends mentioned are best attained. The varying curvatures of 80 the cam-rib impart reciprocating movements to the slides 16 and corresponding tiltings of the blades 9, due to the racks 17 on the slides coaxing with the spur gears 19 on the blades. As will be seen from the drawings, the arrangement is such, as shown best in 85 Figure 1, that as a blade commences its forward sweep above the shaft 7, the blade advances almost edgewise through the air, and as the blade commences its backward sweep below the shaft 7, the blade advances flatwise through the air. 90

The operation of the parts so far described, is believed to be sufficiently clear from the foregoing description. It will be seen that the construction is exceedingly simple and 95 located and assembled very conveniently between the revoluble frame and the body of the aeroplane, thus to cut down head resistance to the minimum, while, at the same time, positively acting parts are employed 100 throughout and in such a way that transverse or shearing strains relative to any working part of the controlling means actuated by the travel of the rollers relative 105 to the cam-rib, are entirely absent. 110

The means for coaxing with said controlling means in order once during each revolution of frame 6 to forcibly urge a blade to assume a tilt setting the blade to a greater angle of incidence than before, and whereby sudden shocks to the controlling means and other parts will be further minimized, is here embodied by the provision simply of a pair of retractile springs 20 for each blade, the springs of each blade diverging away 125 130

from a point of anchorage at the center of the blade and thence running along a flat of the blade to points of anchorage on side members 6^a and 6^b of the revoluble frame, as shown with particular clearness in Fig. 3; these points of anchorage being so related to the axis of rotation of the associated blade, as best shown in Figs. 1 and 4, that while a blade is arranged to cut the air edgewise as shown at the right of Fig. 1, the springs associated with that blade are most expanded and are storing energy to be released to aid the rack and gear means also associated with that blade in doing the comparatively difficult work, during the travel of the blade from the position shown at the right in Fig. 1 to the position shown at the left in Fig. 1, of causing the blade to take a quarter turn in a counter-clockwise direction thereby gradually to throw the blade toward and to a condition where it will have flatwise movement against the air. It will be noted, nevertheless, that the work of shifting the blades toward and away from flatwise movement through the air, is done solely by the cam and the cam-operated rack and gear means; the springs 20 having the sole but exceedingly important function of balancing or compensating for strains on said cam and rack and gear means at all times.

The operation of the propelling and controlling means, with the latter including the intermittently working means described in the last paragraph, should be sufficiently clear from the foregoing; and it will, therefore, be seen that the present invention provides a construction well adapted to satisfy all the objects set forth.

40 I claim:—

1. In a propeller for airships of the type including a revoluble support carrying eccentrically thereon a rotatable propeller blade, the combination of a fixed member carrying a continuous cam surface, and an operative connection to the blade and actuated by relative movement between said cam surface and the revoluble support, thereby to adjust the blade angularly on the support at different points in the path of revolution of the support, said connection including a cam-follower, a rack carrying the cam-follower and reciprocated thereby, and a gear engaging the rack and fixed on the blade concentric with its axis of rotation.

2. In a propeller for airships, comprising a revoluble support, a propeller blade mounted in the frame, a fixed ribbed cam, a sliding rack, a pair of rollers carried by the rack and engaging opposite sides of the ribbed cam, and a pinion on the shaft of the propeller blade and with which the rack engages.

3. In a propeller for airships of the type including a revoluble support carrying eccentrically thereon a rotatable propeller blade, the combination of a fixed member, an operative connection between the fixed member and the blade to variously tilt the blade on the revoluble support at different points in the path of revolution of the latter, one of said blade tilts being to move the blade to increase its angle of incidence, and means automatically functioning to forcibly urge the blade thus to increase its angle and so aid said operative connection in tilting the blade to increase its angle of incidence.

4. In a propeller for airships of the type including a revoluble support carrying eccentrically thereon a rotatable propeller blade, the combination of a fixed member, an operative connection between the fixed member and the blade to variously tilt the blade on the revoluble support at different points in the path of revolution of the latter, one of said blade tilts being to move the blade to increase its angle of incidence, and means partially carried by the blade and partially carried by the revoluble member and automatically acting to urge the blade to change its tilt only when the blade is being tilted to increase its angle of incidence.

5. In a propeller for airships of the type including a revoluble support carrying eccentrically thereon a rotatable propeller blade, the combination of a fixed member, an operative connection between the fixed member and the blade to variously tilt the blade on the revoluble support at different points in the path of revolution of the latter, one of said blade tilts being to move the blade to increase its angle of incidence, and spring means connected to the blade and to the revoluble support for urging the blade to assume a different tilt to increase its angle of resistance.

6. In a propeller for air ships, in combination, a revoluble frame having a substantially horizontal axis located substantially midway of its length, a pair of rotatable blades mounted in the frame on longitudinal axes substantially parallel to the frame axis, each said blade being as wide substantially as one-half the length of the frame and the two blades being located on opposite sides of the frame axis, independently movable racks slidably mounted on the frame with one rack substantially in line with the other, gears fixed on the blades, one such gear meshing with each of the racks, a fixed member carrying a continuous cam surface arranged in a plane substantially parallel to the path of revolution of the revoluble frame, and cam-followers directly carried by said racks and directly engaging said cam surfaces.

EBEN GEORGE DOLAND.
